Victor Gainor, New York, N. Y., assignor to Henri Bendel, Inc., New York, N. Y., a corporation of New York

Application August 29, 1935, Serial No. 58,359

Term of patent 14 years

To all whom it may concern:

Be it known that I, Victor Gainor, a citizen of the United States, residing at 10 Riverside Drive, West, city of New York, in the county of New York and State of New York, have invented a new, original, and ornamental Design for a Shoe Insole or Similar Article, of which the following is a specification, reference being had to the accompanying drawing, forming part thereof.

The figure is a plan view of a shoe insole, showing my new design, the ornamentation shown in part is to be applied throughout the entire surface. The design is of no appreciable thickness.

I claim:

The ornamental design for a shoe insole or similar article, as shown and described.

VICTOR GAINOR.
